UNITED STATES PATENT OFFICE.

JOSEPH SAWDON, OF QUINCY, ILLINOIS.

DUPLEX ENVELOP.

1,303,968.

Specification of Letters Patent. Patented May 20, 1919.

Application filed January 21, 1918. Serial No. 213,028.

To all whom it may concern:

Be it known that I, JOSEPH SAWDON, a citizen of the United States of America, and resident of Quincy, county of Adams, and 5 State of Illinois, have invented a certain new and useful Improvement in Duplex Envelops, of which the following is a specification.

This invention contemplates a duplex envelop having a relatively small compartment to hold a letter, and a relatively large compartment to hold printed matter, so that the two things, although subject to different postal rates, will be practically inclosed by 10 one and the same envelop, the smaller compartment being sealed when transmitted through the mails, and the larger compartment being left open.

The object of the invention, therefore, is 20 to provide an improved construction and arrangement whereby things which are ordinarily subject to different postal rates, and which are usually sent in separate envelops or wrappers, may be inclosed in practically one and the same envelop, so that the two things may not become separated and will arrive at their destination together.

It is also an object to provide certain 30 details and features of construction and combinations tending to increase the general efficiency and desirability of a duplex envelop of this particular character.

To the foregoing and other useful ends, 35 the invention consists in matters hereinafter set forth and claimed.

In the accompanying drawings:—

Figure 1 is a front elevation of a duplex envelop embodying the principles of the invention, showing a portion of the front wall broken away to show the construction.

Fig. 2 is an enlarged vertical section on line 2—2 in Fig. 1.

Fig. 3 is a perspective of the envelop shown in Fig. 1, but without the means to form the relatively small compartment.

Fig. 4 is a perspective of said means for forming the relatively small compartment.

Fig. 5 is a view similar to Fig. 1, showing a different form of the invention.

Fig. 6 is a view similar to Fig. 1, showing a different form of the invention.

Fig. 7 is an enlarged vertical section on line 7—7 in Fig. 6.

Fig. 8 is an enlarged detail section on line 8—8 in Fig. 6.

As thus illustrated, and referring to Figs. 1 to 4 inclusive, the invention comprises an envelop 1 of any suitable form or character, having one end thereof provided with a flap 2 to be secured in place by the usual fastening device, or by any suitable means. The front wall of the envelop is provided with a longitudinal slot 3, and with printed lines 4, these lines and said slot inclosing a rectangular area on the front of the envelop. A sheet of paper 5 is provided with end flaps 6, and with an upper flap 7 and a lower flap 8, all of these flaps being preferably provided with mucilage for securing them in place on said envelop. This is done by inserting the sheet of paper 5 inside of the envelop 1, and by sticking the flaps 6 and 8 to the inner surface of the front walls of said envelop, and by bending down the flap 7 and inserting this flap outwardly through the slot 3. An adhesive strip of paper 9 is then applied to the inner upper edge of the sheet 5, and to the inner surface of the front wall of the envelop 1, whereby a pocket or compartment is formed inside of said envelop, which can be entered by raising the flap 7 and inserting the letter or other article downward through the slot 3, in a manner that will be readily understood. The flap 7 is then folded downward and moistened and caused to adhere to the outer surface of the front wall of the envelop 1, thus sealing the slot 3 and thereby closing the relatively small compartment.

The printed matter, or other matter which is subject to a smaller postal rate, is then inserted in the envelop 1, and the flap 2 is then secured in place by the fastening device, but not sealed. In this way, the letter inserted in the smaller compartment is sealed, and the proper postage is then applied at 10, while a stamp for the proper postage is applied at 11 for the contents of the larger compartment. In this way, the two things which are subject to different postal rates, and which are ordinarily sent in separate envelops, or mailed separately, are really inclosed in one and the same envelop, but are so segregated from each other that the postal laws are complied with, the first-class mail being sealed, while the third-class matter is left open or accessible in the larger compartment. But the two things are inseparable, and will arrive at their destination at the same time and will thus be presented to the addresses at the same time and

together, practically, of course, in one and the same envelop.

The address can be placed on the envelop in any suitable position, but is preferably applied to the rectangular area inclosed by the slot 3 and the lines 4, while the return card of the addresser may appear at the upper left hand corner of the envelop in the usual manner. Also, the return card of the addresser may appear on the outer surface of the flap 7, at the left, so that each piece of mail is practically complete.

As shown in Fig. 5, the construction is practically the same as that shown in preceding figures, but in this case the front wall of the envelop 12 is provided with a vertical slot 13, and with an opening 14 to expose the address on the latter, so that it is not necessary to address the envelop. The sheet of paper to provide the relatively small compartment has the top and bottom flaps 15 and 16 secured to the inner surface of the front wall of the envelop 12 and has the end flap 17 secured in place in the same way, but the other end flap 18 is inserted outward through the vertical slot 13, and is then moistened and caused to adhere to the front surface of the envelop 12 when it is desired to seal the letter inclosed in this relatively small compartment. With this construction, therefore, the letter compartment is left open at the end, whereas in Figs. 1 to 4, inclusive, the letter compartment is left open at the upper edge or top thereof.

In Figs. 6, 7 and 8, the construction comprises an envelop 19 to inclose printed matter or other inferior class mail matter, and may be constructed like the envelop previously described. In this case, however, the front wall of said envelop 19 is not provided with a slot, and the relatively small compartment for the letter or first-class mail matter is formed by a smaller envelop 20 which has its rear side glued or otherwise secured to the front surface of the envelop 19, but with the flap 21 thereof left loose, so that the letter can be inserted in this envelop 20 in the usual manner. As shown, said envelop 20 has an opening 22 for the purpose of exposing the address on the letter, so that it is not necessary to address the envelop. After the letter is inserted in the envelop 20, the flap 21 is then moistened and then caused to adhere to the outer surface of the envelop 19, thereby sealing the letter. It is obvious, therefore, that the invention may be used in various ways, and in various forms of envelops. The form shown in Figs. 6 to 8, inclusive, involves the construction of two complete envelops, which are afterward fastened together, so that more paper or other material would be employed in the manufacture of envelops of this form than would be necessary in the envelops shown in Figs. 1 to 5, includ-

sive. Preferably, as shown, the smaller compartment is outlined upon the face of the envelop, and this is true of Figs. 1, 5 and 6, as in Figs. 1 and 5 the smaller compartment is outlined by the printed lines on the face of the envelop, while in Fig. 6 the smaller compartment is outlined by the edges of the smaller envelop 20, whereby the two compartments are each well defined in the structure. Also, in each of the different forms of the invention shown and described, the smaller compartment has a sealing flap which may be sealed, by causing it to adhere flatwise upon the face of the envelop—that is to say, upon the main front wall of the larger envelop. Ordinarily, things subject to different postal rates are sent in separate envelops, but it is a matter of common knowledge that this method is productive of considerable trouble and annoyance, for the matter which is subject to inferior postal rates usually arrives some time after the envelop containing the letter. Also, the two things arriving separately, one or the other is often lost or mislaid. With the construction shown and described, however, the letter and the printed matter, or matter subject to a less postage, will always arrive together and will be handed to the addressee in practically one and the same envelop, but in a manner that complies with the postal laws, one being sealed and the other unsealed, and each having its own proper postage. The invention, therefore, is not limited to the exact construction shown and described. 100

It is obvious that the larger or main envelop can be constructed in different ways, and in Fig. 5 the construction may involve an inner strip of paper 23, similar to the strip of paper 9 shown in Fig. 1, which may be employed to secure the inner sheet of paper to the front wall of the main or larger envelop. Furthermore, and while for the purpose of illustration, to show how the invention may be used, the larger envelop has been described as containing printed matter, it will be understood that it may contain anything else that can be sent through the mails for less postage than the letter. In any event, though, as previously explained, and as shown and described, the invention comprises a plurality of separate compartments, but each compartment may be of any suitable character, more especially the one for the printed matter, as this larger compartment, which is intended to contain or hold various things, may be of any suitable form or character, such as the various envelops or wrappers employed in sending the newspapers or other printed matter, or any other desired article which may be transmitted through the mails. 115

Preferably, as shown in Figs. 1, 5 and 6, the smaller compartment is disposed adjacent the lower edge of the larger compart- 120

ment, so that the address is about where it would ordinarily be written relatively to the four edges of the larger compartment, and in each case the small compartment is on the front of the large compartment, the rectangular outline of the small compartment appearing in each case on the face of the envelop.

What I claim as my invention is:—

- 10 1. A duplex envelop comprising a relatively small compartment adapted and intended to be sealed after the insertion of a letter therein, and a relatively large compartment arranged back of the small compartment, so that the small compartment is on the front of the large compartment, and which large compartment is adapted to be left open or unsealed at the back of the envelop after the inclosure of printed matter or an article therein, the envelop having a single addressing space for both compartments on the face of the small compartment, the two compartments being permanently united in one unitary structure, with the small compartment on the face of the main envelop, so that the two compartments may contain things which are subject to different postal rates, the contents of the larger compartment being subject to inspection and removal without opening the smaller or sealed compartment, whereby the two things will not become separated and will be delivered as a single piece of mail to the addressee, and with the total postage all on the front of the envelop but separately applied to each compartment.
- 20 2. A stucture as specified in claim 1, said relatively small compartment being formed by a sheet applied to the inner surface of the front wall of the envelop, said sheet having a loose flap, said envelop having a slot in its front wall through which said flap projects outwardly, so that after the letter is inserted through said slot into the relatively small compartment the flap may then be sealed by causing it to adhere to the outer surface of the envelop, said small compartment being disposed adjacent the lower edge of the large compartment, and an inner retaining strip back of said flap to secure the sheet to the front wall of the envelop.
- 30 3. A duplex envelop comprising a plural-
- 35 4. A duplex envelop comprising a relatively large rectangular compartment for printed matter, or for other mail matter less than first class, and a relatively small letter compartment on the front of said large compartment, so that one address applied to the small compartment is sufficient for both kinds of mail matter, with a flap on the rear side or back of the envelop for accessibly closing the large compartment, and a flap on the face or front side of the envelop for sealing the small compartment, the rectangular outline of the small compartment appearing on the face of the envelop.
- 40 5. A duplex envelop comprising a relatively large rectangular compartment for holding mail matter less than first class, a relatively small rectangular compartment for a letter on the front of said large compartment, the smaller comparement being entirely within the area of the larger compartment, so that one address applied to the smaller compartment is sufficient for both kinds of mail matter, the two compartments being inseparable, means to accessibly close the larger compartment, and a loose flap on the face of the envelop for non-accessibly sealing the smaller compartment after the insertion of the letter therein.

Signed by me at Quincy, Adams county, Illinois, this 15th day of January, 1918.

JOSEPH SAWDON.
